GEORGE A. BINDER, OF CHICAGO, ILLINOIS, ASSIGNOR TO ROBERT MALCOM, OF CHICAGO,
ILLINOIS

GOOGLES

Application filed March 31, 1932. Serial No. 602,129.

My invention relates more particularly to goggles involving eye-cups adapted to more or less closely fit about the eyes of the wearer; the invention having for its object the provision of means associated with the lenses whereby proper circulation of air about the lens and within the lens holding end of the eye-cup may be obtained and the formation of condensate on the lens interior or fogging 10 of the lens prevented.

My invention also involves means whereby the degree of air circulation may be regulated in keeping with the desires and needs of the wearer under varying conditions of use.

15 The objects and advantages of my invention will be readily comprehended from the following detailed description of the accompanying drawing wherein:

Figure 1 is a transverse sectional elevation 20 of an eye-cup with my improved means arranged for a maximum degree of ventilation.

Figure 2 is a similar view of an eye-cup with my improved means arranged for a 25 minimum degree of ventilation.

Figure 3 is a perspective view of an element of my improved means.

Figure 4 is a similar view of the same element, looking at the opposite side.

30 Figure 5 is a perspective view of a segment of the lens holding ring.

My invention is especially adapted to goggles of the type employed by mechanics and machinists when working with welding 35 torches, abrading machines, metal chipping and the like, requiring full eye protection and therefore goggles which will conform more or less to the face and fit comparatively closely about the eyes. Considerable difficulty and discomfort has been encountered 40 with goggles of this character, due to lack of proper ventilation within the eye-cups and particularly adjacent to the inner face 45 or side of the lens, causing the lens to become fogged and vision made indistinct.

For purposes of exemplification, I have disclosed my invention applied to a goggle eye-cup of the type especially adapted to be 50 used by a mechanic whose eye-sight necessi-

tates the constant wearing of eye-glasses or spectacles.

Therefore, the temple side of the eye-cup wall 10 is shown moulded or provided with an outward off-set or spectacle arm receiving 55 socket at 11 disposed transversely of the eye-cup wall from outer or lens end toward the inner or face engaging perimeter, where it terminates in a slotted ear 12 intended to receive the usual headstraps whereby the goggle 60 is secured in place. As the eye-cup construction thus far described is no part of my invention, further detailed description of the general wall formation of the eye-cup need not be entered into.

65 The eye-cups are usually made of a mouldable material, such as bakelite, so as to provide the wall with sufficient strength and rigidity while at the same time being comparatively light in weight.

70 The wall at the outer or lens receiving end on the eye-cup interior and somewhat removed from the outer perimeter is shown provided with an annular shoulder 13; while the interior of the cup beyond the shoulder is 75 shown threaded to receive the externally threaded flanged ring 14, whose flange is intended to lap the outer perimeter of the eye-cup as shown; the ring 14 being intended to hold the lens 15 in place.

80 The annular shoulder 13 is shown provided with a plurality of circumferentially spaced notches or grooves, as at 16, disposed transversely of the shoulder; while the threaded main body portion of the ring 14 is 85 likewise provided with a plurality of cut-out portions or slots disposed transversely of the inner threaded portion as shown at 17 in Figures 2 and 5.

89 The lens 15, as clearly shown in Figures 1 and 2, is of a diameter materially less than the diameter of the threaded portion of the eye-cup; and the lens 15 is provided with a beveled perimeter 18 tapering inwardly toward the outer face of the lens. This beveled 95 edge of the lens will cause the lens to be centered when the ring 14 is screwed into contact therewith and as a result an annular space at 19 will be provided beneath the ring 14 and surrounding the edge of the lens 15. 100

The lens on its inner side is also preferably provided with a slight oppositely disposed taper at 20. This inner bevel or taper 20 is intended to seat on an annular member 5 or ring 21 shown in detail in Figures 3 and 4.

The ring 21 seats on the annular internal shoulder 13 as shown in Figures 1 and 2. The ring 21, which may be of any suitable light material, as for example aluminum, has one 10 face provided with an annular groove 22; and at circumferentially spaced points is provided with the transverse notches or slots 23 extending through the walls on opposite sides of the circumferential groove 22, see Figure 15 3; with the notches or slots 23 on the inner wall or perimeter of the ring extending down and through to the opposite side or annular face of the ring 21, as shown at 24 see Figures 3 and 4; while the notches or slots 23 on the 20 outer perimeter of the ring are of depth substantially equal to the depth of the annular groove 22.

When the ring 21, which is of larger diameter than the lens, is arranged in the eye-cup 25 with the annular groove 22 in the ring disposed toward the lens 15, the inner or lower ends 24 of the slots 23 will communicate with the goggle interior beneath the lens, while slots 23 will register or communicate with the 30 annular space 19 with which the slots 17 in the lens holding ring 14 also communicate. It is apparent, therefore, that a plurality of continuous air passages, leading from the exterior to the interior of the eye-cup, or vice 35 versa, will be provided as shown at 25 in Figure 1.

Furthermore, these continuous passages 25 also communicate with the annular groove 22 in the face of the ring 21, thus allowing some 40 of the air to flow around in the groove and to discharge through the lower or inner ends 24 of the slots 23. It is apparent that circulation 45 of air through the eye-cup and across the inner side of the lens is permitted; and in order to permit such circulation, particularly in eye-cups as shown which are adapted to fit closely about the eyes, I show the side wall of the eye-cup preferably provided with two screened openings at 26, 26.

50 In my improved eye-cup, the lens 15 is not only preferably beveled as shown and stated, but the lens diameter is also preferably sufficiently less than the inner diameter of the threaded wall portion of the eye-cup so that 55 the peripheral edge of the lens intermediate of the opposite bevels 18 and 20 will merely engage at the inner peripheral edge of the ventilating ring 21, as shown in Figures 1 and 2.

60 The lens, therefore, will not overlie or extend flush with the entire annular faces of the ventilating ring and hence will not entirely cover the ends of the slots 23.

65 At the same time, with the slots 17 in the lens clamping ring made of sufficient depth

as shown, the outer ends of these slots will remain uncovered and therefore permit air to enter the air space 19 beneath the threaded end of the lens clamping ring, see Figures 1 and 2, this air space in turn communicating with the annular groove 22, which, in turn, communicates with the slots 23. 70

With the ring 21 arranged with its annular groove 22 disposed outwardly, namely toward the lens as shown in Figure 1, the maximum degree of ventilation is obtained. 75

If for any reason a lesser amount of ventilation or air circulation is desired, the wearer need merely remove lens clamping ring 14 and the lens 15 and then reverse the ventilating ring 21 by disposing the grooved side shown in Figure 3 inwardly or away from the lens, with the ungrooved side shown in Figure 4 disposed toward the lens as shown in Figure 2, and thus obtain a minimum degree of circulation, as a lesser amount of the air, which passes through the slots 17 in the lens clamping ring 14 into the air chamber or space 19, can pass through the uncovered portion 24 at the base of the slots 23 to the interior of the eye-cup, or vice versa; this being possible because the extreme peripheral edge of the lens merely rests on the inner perimetrical rim of the ventilating ring 21. 80 85 90

It is apparent that the inner ends 24 of slots 23 in the ring will communicate with the goggle interior. Furthermore, as the slots 23 communicate with the annular groove 22 in ring 21, a minute amount of air will enter groove 22 and allowed to circulate through the slots 16 formed in the ring-seat or shoulder 13 of the goggle. As is evident, a lesser amount of air circulation is obtainable with the ring 21 arranged as shown in Figure 2 than is the case where the entire 100 104 groove 22 is open to the annular air space 19 at the perimeter of the lens. 95

It is apparent that although air circulation about the lens is permitted, the passages are not only rather minute but of an indirect nature thus preventing passage of undesirable foreign particles. 110

I have illustrated what is believed to be a simple embodiment of the invention which I described in terms of description and not 115 as terms of limitation as structural modifications are possible without, however, departing from the spirit of my invention.

What I claim is:

1. A goggle comprising a pair of eye-cups 120 the outer ends whereof are each adapted to receive a lens; the inner wall of each cup at a distance removed from the outer end being inwardly enlarged and provided with circumferentially spaced air passages; a ring seatable on said enlargement adapted to provide a seat for the lens, said ring on its inner diameter and transversely of one annular face having a plurality of slots spaced circumferentially and adapted to register with said air 125 130

passages in the eye-cup wall enlargement; the lens diameter being such that the peripheral edge of the lens rests at the inner peripheral edge of said ring and leaves the end of 5 the slots in said ring uncovered; and means cooperating with the cup-wall whereby the lens will be maintained in the eye-cup and seated on said ring.

2. A goggle comprising a pair of eye-cups 10 the outer ends whereof are each adapted to receive a lens, a shoulder on each cup interior; a ventilating ring seatable on said shoulder, said ring on its inner perimeter having spaced apart slots extending transversely of one annular face of the ring to the outer perimeter of the ring; the lens being seatable on the inner peripheral edge of said ring so as not to cover said slots; and means whereby the lens and said ring are 20 secured in place.

3. A goggle comprising a pair of eye-cups whose outer ends are internally threaded and provided with an annular shoulder below the threads, said shoulder having transverse 25 air passages circumferentially spaced apart; a ventilating ring seatable on said shoulder, said ring having an annular groove and transverse slots extending into the inner perimeter of the ring, said slots being adapted to register with the air passages in said shoulder; a lens provided with a beveled perimeter adapted to seat on the inner peripheral edge of said ring; and a flanged ring externally threaded to screw into the threaded end of 35 the cup and engage the beveled edge of the lens, said ring being provided with circumferentially spaced slots in the lens engaging perimeter thereof.

4. A goggle comprising an eye-cup provided with an air admitting opening in the side wall and threaded at its outer end and having a circumferentially arranged seat on its interior adjacent the outer end formed to provide air passages transversely thereof; a 45 ventilating ring seatable on said seat, one face of the ring having an annular groove, circumferentially spaced slots disposed transversely of the grooved face and of the inner perimeter of the ring and terminating at the opposite face of the ring, said slots being adapted to register with the air passages of said seat; a lens provided with a beveled perimeter adapted to seat on the inner peripheral edge of said ring without covering the slots 55 in the ring; and a threaded ring adapted to screw into the threaded end of the cup and to engage the beveled perimeter of the lens, the ring being provided with circumferentially spaced slots adapted to permit air to 60 pass about the perimeter of the lens.

5. A goggle comprising an eye-cup provided on its interior adjacent the outer end with a circumferentially arranged seat; a ring arranged on said seat and having transversely disposed air passages; a lens of small-

er diameter than the external diameter of said ring and adapted to seat on the inner peripheral edge of said ring so as to leave an annular space between the perimeter of the lens and the wall of the eye-cup communicating with the air passages in said ring; and a lens retaining ring provided with air passages adapted to communicate with said annular space, whereby air circulation about the lens is permitted. 675

6. A goggle comprising eye-cups each provided on its interior adjacent the outer end with a ring holding portion formed to provide air passages; a ring seatable on said portion and provided with an annular groove 680 and with transversely arranged slots from the outer to the inner perimeters thereof and extending to the opposite face of the ring; a lens of diameter less than the inside diameter of the cup and seatable on the inner perimeter of the ring so as to leave the ends of the slots uncovered and in communication with the annular space about the perimeter of the lens; and a lens clamping ring adapted to be secured to the eye-cup and in spaced 685 relation with the first mentioned ring, said lens clamping ring having air passages therethrough communicating with said chamber. 690

7. A goggle comprising eye-cups, a lens 695 seating ring in each eye-cup provided with air passages communicating with the cup interior and with the lens seating side; a lens seatable on the ring and of diameter less than the inside diameter of the cup so as to provide 700 an annular air space about the perimeter of the lens, said space communicating with the air passages in the lens seating ring; and means for holding the lens in place. 705

8. A goggle comprising eye-cups having 710 imperforate side walls at the lens receiving ends, a lens seating ring in each eye-cup provided with air passages extending from the upper to the lower annular sides of the ring 715 and communicating with the eye-cup interior and with the outer end thereof; a lens seatable on said ring and provided with an annular air space thereabout with which the upper ends of said air passages communicate; and a lens clamping ring arranged at the outer 720 ends of the eye-cups and provided with air 725 passages adapted to communicate with said annular air space disposed about the perimeter of the lens. 730

9. A goggle comprising eye-cups, each cup 735 on its interior being provided with lens supporting means adjacent the outer end of the cup, said means being arranged to provide air passages; the lens being of diameter less than the inside diameter of the cup so as to provide an annular air space about the lens perimeter which communicates with said air 740 passages; and a lens clamping ring adapted to be secured to the eye-cup wall to maintain the lens in position, said ring having air pas- 745 750 755 760 765 770 775 780 785 790 795 800 805 810 815 820 825 830 835 840 845 850 855 860 ages arranged to communicate with the annular air space about the lens, whereby air circulation on opposite sides of the lens is permitted.

- 5 10. A goggle comprising eye-cups; a lens seating ring in each eye-cup provided with an annular groove in one of its annular faces, spaced apart slots disposed transversely of said groove and slots on the inner perimeter 10 of said ring connected with said transverse slots; a lens of diameter less than the outside diameter of said ring so as to provide an annular air space about the perimeter of the lens communicating with the first named slots 15 in said ring; and lens clamping means adapted to engage the outer face of the lens and formed to provide air passages at the outer end of the eye-cup and communicating with the annular air space about the lens above 20 said lens seating ring.
11. A goggle comprising eye-cups; a lens seating portion in each eye-cup provided with air passages leading from the upper face of said portion to the eye-cup interior; a lens 25 of diameter less than the inner diameter of the cup so as to provide an annular air space about its perimeter communicating with the upper ends of the passages in said seating portion, the lens being seatable at the inner 30 perimeter of said portion; and a lens clamping ring provided with air passages above said lens communicating with the annular space about the lens.
